Jack Bloch, Leominster, Mass., assignor to Foster Grant Co., Inc., Leominster, Mass., a corporation of Delaware

Application February 3, 1958, Serial No. 49,488

Term of patent 14 years

(Cl. D57—1)

FIG. 1

Fig. 1 is a front elevational view of a sun-glass frame front, showing my new design;

Fig. 2 is a top plan view thereof; and

Fig. 3 is a fragmentary rear view including one half of the frame front taken from the center of the bridge portion to the end portion of the front.

The dominant features of the design are shown in full lines in the drawing.

I claim:

The ornamental design for a sunglass frame front or the like, substantially as shown and described.
